UNITED STATES PATENT OFFICE

164,922

TEXTILE FABRIC

Bernard D. Gould, New York, N. Y.

Application March 30, 1949, Serial No. 1,720

Term of patent 14 years

(Cl. D92—1)

To all whom it may concern:

Be it known that I, Bernard D. Gould, a citizen of the United States and a resident of the city of New York, county of New York, and State of New York, have invented a new, original, and ornamental Design for a Textile Fabric, of which the following is a specification, reference being had to the accompanying drawing, forming a part thereof.

The figure is a plan view of a full width of a textile fabric, showing my new design.

The seven stripes on the fabric gradually increase in width and density of shade from the selvage at the top of the figure to the selvage at the bottom thereof.

I claim:

The ornamental design for a textile fabric, as shown and described.

BERNARD D. GOULD.
